C 12,177

Design No. 12,177, dated February 22, 1881.

UNITED STATES PATENT OFFICE.

JOHN LOCHNER, OF NEW YORK, N. Y., ASSIGNOR TO POTTIER & STYMUS MANUFACTURING COMPANY, OF SAME PLACE.

DESIGN FOR INTERIOR FINISH OF RAILWAY-CARS.

SPECIFICATION forming part of Design No. 12,177, dated February 22, 1881.

Application filed October 28, 1880. Term of patent 7 years.

To all whom it may concern:

Be it known that I, JOHN LOCHNER, of New York city, New York, have originated a new and ornamental Design in Wood for the Interior Finish of Railway-Cars, of which the following, together with the accompanying photographs, forms a full, clear, and exact description.

My design is more especially intended for the interior of sleeping-cars, and to those parts of the interior known as the "bulk-heads," which are the transverse partitions containing the door, which gives admittance from the platforms or end compartments of the car to the central or main compartment containing the seats and berths, and also to the fronts of the upper or folding berths, known as the "bunk-fronts."

My design consists, mainly, in a molded and paneled facing of the said parts in light and dark mahogany, with intervening narrow borderings decorated with inlayings of rose-wood, as hereinafter fully set forth, whereby a very agreeable effect is produced, of a novel and peculiarly-appropriate character, for the described purpose.

Figure 1 of the annexed photographs gives a view of the bulk-head, and Fig. 2 a view of the bunk-front, embodying my design.

In Fig. 1, *a* indicates the door in the bulk-head, and *b b* the ends of the bunks which occupy the upper corners of the car-body, inclining from the top and curving toward the sides, as shown. The wall or face of the bulk-head 35 above and on either side of the door is paneled and molded, and also decorated with inlayings in the marginal frame or borderings, as shown. Thus a prominent molding, *h*, extends around the edge of the doorway and 40 terminates at a broad horizontal molding, *c*, running from the doorway to the sides of the car at about a level with the middle of the door or the tops of the seats. The space on either side of the door below this molding *c* is 45 paneled with two plain rectangular panels, as shown, which sufficiently relieve this part of the surface, no elaboration being here necessary, as these parts are not prominent, being partly concealed by the seats. Above the 50 molding *c c* the molding and paneling are more

elaborate. Two narrow rectangular and grooved moldings, *d d*, run parallel with each other around the top and sides of the door and over the molding *c*, forming a border to the door and the paneled field on either side thereof, which border is decorated with inlayings in the squares formed where the said moldings intersect, and also in the upright borders at either side of the door, and also in the horizontal border directly over the door. The character of the inlaid design in the squares is that of two oak-leafed quarterfoils superimposed upon each other, while the inlaying on the upright borders is a symmetrical foliation simulating a flowering-vase, and the design in the border over the door is that of two recumbent dragons facing each other, with a central fan-shaped device between them, while their tails terminate in a curved foliation which returns upon itself. Now, a molding, *e*, similar to the border-moldings *d*, rises parallel with the side of the car for a short distance, and thence curves and inclines upward and inward parallel with the inclined front and curved base of the bunks, and finally meets with one of the border-moldings *d*, thus inclosing a 70 approximately triangular panel, *f*, which harmonizes well with the inclined front of the bunks. The field of this panel is preferably lower than the surrounding field, leaving a 75 margin, *g*, within the molded border, on the same level as the surrounding field, and this panel is preferably grooved with parallel grooves at broad intervals, simulating boarding, and slightly ornamented with a few 80 simple grooved traceries along the curved side of the panel, so as to give a more elaborate 85 finish to the large surface of the panel; but the panel may be plain without departing seriously from the general effect.

It will be observed from Fig. 2 that the design of the finished face of the inclined front and curved base of the bunk is of the same character as that of the bulk-head. Thus Fig. 2 shows the front of one complete bunk 90 or berth which is divided into three paneled sections, as illustrated. The central panel is the largest, and has at the top a semicircular indenture, while the outer panels are plain 95 rectangles of narrower size. The borderings 100

between the paneled sections have the same moldings with ornamental inlayings, (substantially the same as in the case of the bulk-head just described,) so as to harmonize therewith.

5 The border over the bunks or under the ventilators contains inlays similar in the intersecting squares, but over the central paneled sections the inlays consist of six-leaved rosettes, each separated from the other by intervening

10 leafy devices similar to an oak-leaf.

Now, the entire wood-work described is composed of a novel blending and combination of woods in the design shown, which adds greatly to its effect—that is, two shades of 15 mahogany are used in the field and the moldings of the paneled sections and borders, the fields being, say, all of dark mahogany, and the moldings all of light mahogany, or vice versa, the former being the best—while all the 20 inlayings are of rose-wood. This combination of woods, with substantially the formal design shown, constitutes a distinct feature of my complete design, and it gives a very soft, refined, and agreeable effect; for while the colors used 25 are all of the red or brown series, yet sufficient contrasts are produced between the darkly-

brilliant rose-wood inlays and the light mahogany molding with the dark mahogany fields or panels to give a degree of liveliness, while at the same time securing great harmony, combined with a refined contrast or variation, which attracts, pleases, and rests the eye, all abrupt or strong changes of color or form being avoided, so that the prevailing tone given to the interior of the car is soft and 30 pleasing, warm, and conducive to repose, as befits cars intended for night travel. •

What I claim is—

The design in woods for the interior finish of cars, herein set forth, consisting of molded 40 and paneled facings with marginal borderings, the same being formed of a combination of light and dark mahogany, respectively, in the moldings and fields of the panels and borderings, with inlayings of rose-wood in the field 45 of the borderings, substantially as specified and illustrated.

JOHN LOCHNER.
